CLAIM

The ornamental design for an inertial transmission device, as shown and described.

DESCRIPTION

FIG. 1 is a top perspective view of an inertial transmission device;

FIG. 2 is a front view of FIG. 1; the rear view, the left side view and the right side view thereof are identical to the front view and are not shown;

FIG. 3 is a top view of FIG. 1;

FIG. 4 is a bottom view of FIG. 1;

FIG. 5 is a bottom perspective view of FIG. 1; and,

FIG. 6 is a sectional view taken along line 6-6 of FIG. 3. The broken lines shown on the drawings are included for the purpose of illustrating unclaimed features of the inertial transmission device and form no part of the claimed design.
